DESIGN FOR A FLEXIBLE EAR CUSHION FOR ATTACHMENT TO TELEPHONE RE- CEIVERS

Mary N. Kesh, Detroit, Mich.

Application July 25, 1940, Serial No. 93,931

Term of patent 14 years

To all whom it may concern:

Be it known that I, Mary N. Kesh, a citizen of the United States and residing at Detroit, in the county of Wayne and State of Michigan, have invented a new, original, and ornamental Design for a Flexible Ear Cushion for Attachment to Telephone Receivers, of which the following is a specification, reference being had to the accompanying drawing, forming part thereof.

Fig. 1 is a front elevational view of a flexible ear cushion for attachment to telephone receivers showing my new design.

Fig. 2 is a side elevational view thereof.

Fig. 3 is a rear elevational view thereof.

Fig. 4 is a sectional view thereof taken through the mid portion of Fig. 2.

The characteristic features of my design reside in the portion shown in full lines.

I claim:

The ornamental design for a flexible ear cushion for attachment to telephone receivers, as shown and described.

MARY N. KESH.
